DESIGN FOR A UTENSIL SUPPORT FOR A COOKING RANGE

Grover F. Whitehead, Rockford, Ill., assignor to
Geo. D. Roper Corporation, Rockford, Ill., a corporation of Illinois

Application June 14, 1941, Serial No. 101,467

Term of patent 14 years

To all whom it may concern:

Be it known that I, Grover F. Whitehead, a citizen of the United States, residing at Rockford, in the county of Winnebago and State of Illinois, have invented a new, original, and ornamental Design for a Utensil Support for a Cooking Range, of which the following is a specification, reference being had to the accompanying drawing, forming part thereof.

In the drawing:

Fig. 1 is a perspective view of a utensil support for a cooking range showing my new design, and
Fig. 2 is a top plan view thereof.

I claim:

The ornamental design for a utensil support for a cooking range, substantially as shown.

GROVER F. WHITEHEAD.
